UNITED STATES PATENT OFFICE.

CHARLES J. LINDSTROM, OF CLINTON, MISSOURI.

SAFETY-GUARD.

1,354,048.

Specification of Letters Patent. Patented Sept. 28, 1920.

Application filed March 15, 1920. Serial No. 366,086.

To all whom it may concern:

Be it known that I, CHARLES J. LINDSTROM, a citizen of the United States, residing at Clinton, in the county of Henry and 5 State of Missouri, have invented certain new and useful Improvements in Safety-Guards, of which the following is a specification.

This invention relates to improvements in safety devices and has for its object to 10 provide a quick acting guard to protect bank clerks and others handling considerable money, from hold-up men.

Another object of the invention is to provide means whereby a bank, or other cashier 15 may protect himself from robbers and at the same time place himself in position to shoot the would be robber.

With the above and other objects in view, I have invented the device illustrated in the 20 accompanying drawings in which—

Figure 1 is a sectional view of a cashier's cage embracing my invention.

Fig. 2 is a similar view showing certain parts in changed position.

Fig. 3 is an elevational view of a modification of the device in the act of being sprung, certain parts being broken away.

Fig. 4 is a similar view of another modification, and

Fig. 5 is a diagrammatic view of a spring releasing device.

Like reference characters indicate like parts throughout the following specification and in the several views in the drawings in 35 which 1 indicates a cashier's cage, having a front wall 2 in which is provided a window 3 above the desk 4, the inner part of the desk extending through the window to form a customer's counter 5. Mounted under the 40 desk and in alinement with the wall 2, is a tube 6, in which is seated a coil spring 7 upon the upper end of which is mounted an armour steel sheet 8 which is of a size to completely close the window 3. The upper 45 edge 9 of plate 8 is provided with a strip of rubber or other suitable material 10 of a width and length to completely fit the counter-sink into the widened slot 11 in counter 5 through which the plate 8 is adapted to 50 pass and normally keep this slot closed, the upper surface of said member 10 being flush with and painted to match the surface of the counter 5. Normally the spring 7 is held under compression, as at 12, by

means of a cross head 13 on the end of a 55 horizontal rod 14, said member 13, operating through a horizontal slot 15, in the tube 6. The rod 14 operates between rollers 16 and 17 on the upper ends of the standards 18 and 19, and the roller 20 carried by the brace bar 60 21 which may be of strap iron, and which extends around the tube 6 and is returned upon itself. A similar bar 22 is also carried by the standards 18 and 19. The outer end of the bar 14 has a spring 23 coiled there-around between said standard 19 and the pivot joint 24 connecting said bar 14 and a link 25. When the bar 14 and its cross head 13 are shoved in to hold spring 7 under compression, spring 23 is also held under compression, the bar 14 being held in position of link 25 the ends of which bear between the pivot 24 of bar 14 and pivot 26 of bar 22. The link 25 is formed of two members connected by a hinge 27 against which a pin 75 28 normally rests, said pin projecting from the upper end 29 of a lever 30 mounted on the pivot 26, the lower end of this lever carrying a foot treadle 31. Any pressure upon the treadle or lower end of lever 30 80 will cause the pin 28 to break the link 25 and release spring 23 which will throw out rod 14, withdraw head 13 from the tube 6, release spring 7, which will instantly throw up plate 8 to close window 3, give the 85 cashier a chance to duck under desk 4, grab his pistol and attack any would be robber through an opening 32 in the wall 33 under the counter 5. Rod 14 carries an electric contact 34 which engages contact 35 on 90 standard 18 closing a circuit which gives a general alarm that the bank is being attacked.

In Fig. 3 I show a modification in which the windows 36 and 37 of a pair of cages 95 (paying teller's and receiving teller's) are simultaneously closed by the plate 38 which is of a width sufficient to close both windows. The trip lever 30 (see Fig. 2) in this case is located between the two cages and a 100 wire 39 extends from near the foot of each teller across the lever 30 so that a slight pressure on said wire by the occupant of either cage will operate said lever 30 to actuate the device.

In Fig. 4 a modification is shown in which the plate 40 is provided with side extensions 41 and 42. This is used in connection

with grated cages, the wings 41 and 42 together with the central plate 40 will provide ample protection for the clerk while ducking to safety under the desk.

5 Having now described my invention, that which I claim to be new and desire to procure by Letters Patent is:

1. The described device consisting of a blind, a spring upon which the blind is 10 mounted and a tube in which the spring is inclosed, said tube being split to accommodate said blind.

2. The described device consisting of a blind, a spring upon which the blind is 15 mounted and a tube in which the spring is inclosed, said tube being split to accommodate said blind, a cashier's desk having a slot through which said blind operates and a head on the blind forming a closure for 20 the slot.

3. The described device consisting of a blind, a spring upon which the blind is mounted and a tube in which the spring is 25 inclosed, said tube being split to accommodate said blind, a cashier's desk having a slot through which said blind operates and a head on the blind forming a closure for 30 the slot, means for holding the spring under compression.

30 4. The described device consisting of a blind, a spring upon which the blind is mounted and a tube in which the spring is 35 inclosed, said tube being split to accommodate said blind, a cashier's desk having a slot through which said blind operates and a head on the blind forming a closure for 40 the slot, means for holding the spring under compression, said means consisting of a cross head.

40 5. The described device consisting of a blind, a spring upon which the blind is mounted and a tube in which the spring is 45 inclosed, said tube being split to accommodate said blind, a cashier's desk having a slot through which said blind operates and a head on the blind forming a closure for 50 the slot, means for holding the spring under compression, said means consisting of a cross head, rollers between which the cross head operates.

55 6. The described device consisting of a blind, a spring upon which the blind is mounted and a tube in which the spring is inclosed, said tube being split to accommodate said blind, a cashier's desk having a slot through which said blind operates and a head on the blind forming a closure for 60 the slot, means for holding the spring under compression, said means consisting of a cross head, rollers between which the cross head operates, said cross head being spring controlled.

65 7. The described device consisting of a blind, a spring upon which the blind is

mounted and a tube in which the spring is 65 inclosed, said tube being split to accommodate said blind, a cashier's desk having a slot through which said blind operates and a head on the blind forming a closure for 70 the slot, means for holding the spring under compression, said means consisting of a cross head, rollers between which the cross head operates, said cross head being spring controlled, means for releasing said last spring control. 75

8. The described device consisting of a blind, a spring upon which the blind is mounted and a tube in which the spring is inclosed, said tube being split to accommodate said blind, a cashier's desk having 80 a slot through which said blind operates and a head on the blind forming a closure for the slot, means for holding the spring under compression, said means consisting of a cross head, rollers between which the cross 85 head operates, said cross head being spring controlled, means for releasing said last spring control, said last means consisting of a pivoted lever.

9. The described device consisting of a blind, a spring upon which the blind is mounted and a tube in which the spring is 90 inclosed, said tube being split to accommodate said blind, a cashier's desk having a slot through which said blind operates and 95 a head on the blind forming a closure for the slot, means for holding the spring under compression, said means consisting of a cross head, rollers between which the cross head operates, said cross head being spring controlled, means for releasing said last spring control, said last means consisting of a pivoted lever, means for holding said last 100 spring under compression.

10. The described device consisting of a blind, a spring upon which the blind is mounted and a tube in which the spring is 105 inclosed, said tube being split to accommodate said blind, a cashier's desk having a slot through which said blind operates and 110 a head on the blind forming a closure for the slot, means for holding the spring under compression, said means consisting of a cross head, rollers between which the cross 115 head operates, said cross head being spring controlled, means for releasing said last spring control, said last means consisting of a prop formed of two 120 members hinged together.

11. The described device consisting of a blind, a spring upon which the blind is mounted and a tube in which the spring is 125 inclosed, said tube being split to accommodate said blind, a cashier's desk having a slot through which said blind operates and a head on the blind forming a closure for

the slot, means for holding the spring under compression, said means consisting of a cross head, rollers between which the cross head operates, said cross head being spring controlled, means for releasing said last spring control, said last means consisting of a pivoted lever, means for holding said last spring under compression, said last means consisting of a prop formed of two members

hinged together, means on said lever for 10 breaking the prop.

In testimony whereof I affix my signature in the presence of two witnesses.

CHARLES J. LINDSTROM.
